UNITED STATES PATENT OFFICE

SHERWOOD M. CHASE, OF COLUMBUS, OHIO, ASSIGNOR TO THE CHASE FOUNDRY AND MANUFACTURING COMPANY, OF COLUMBUS, OHIO, A CORPORATION OF OHIO

COUPLER

Application filed January 2, 1930. Serial No. 417,908.

My invention relates to a coupler.

It is the object of my invention to provide a coupler having a flexible lower jaw which will permit the vehicle on which the coupler is mounted to be taken on steep inclines without dragging the coupler or breaking it.

It is my object to provide a vehicle having a coupler particularly adapted to locations where there are steep inclines or ramps that have an abrupt change of angle from the horizontal floor line.

Referring to the drawings:

Figure 1 is a side elevation showing in a diagrammatic view the operation of the coupler when the vehicle is on a steep ramp and the overhanging coupler portion is adjacent to the horizontal floor line;

Figure 2 is a top plan view of the coupler;

Figure 3 is a section on the line 3—3 thereof;

Figure 4 is a bottom plan view of the hinge jaw coupler; and

Figure 5 is a rear elevation of Figure 3.

Referring to the drawings, 1 is a vehicle frame having rear wheels 2 and forward caster wheels 3.

The coupler which is mounted on one end of the frame 1 by the back plate 4 comprises the following parts. The vehicle casting attaching plate member 4 has an upper, rigid, bifurcated jaw comprised of side walls 5 and 6 which are joined at their forward ends by the guide plate 7. This plate extends downwardly and inwardly to guide the bail into the space between the upper stationary jaw and the lower movable jaw.

The bifurcated side wall members 5 and 6 of the upper jaw have their lower edges inclined upwardly and inwardly, as at 8, and thence horizontally at 9 and downwardly at 10 where they merge into a central pivot casting 11 which forms the support for the shaft 12 that carries the rocking lower jaw 13. A shoulder 13a on the lower jaw is adapted to engage a shoulder 4a on the upper jaw for limiting the downward movement of the lower jaw.

This lower jaw has rearwardly extending spaced arms 14 and 15 which are mounted

upon the shaft 12 on either side of the casting member 11.

This lower jaw 11 is provided with a front bail engaging portion which has an inwardly and upwardly tapered face 16. It has a lower face 17, which latter face engages with the surface of the ground when it is necessary to move the jaw by reason of change of elevation of the truck.

Between the bifurcated portions 5 and 6 of the upper stationary jaw there rocks a bail rocking hook designated 18 which is pivotally mounted on the shaft 19 that is carried in the bifurcated members 5 and 6. This hook is provided with spaced supporting arms 20 and 21 which are carried on the shaft 19. Between these arms is carried a spring 22, one end of which at 23 engages the rear wall 4 and front end of which at 24 engages in a transverse pin 25, the forward portion of the hook yieldingly moving it downwardly. The hook is provided with a hook portion 26 and an upwardly extending finger 27 having an eye 28. This member 27 will engage with the guide plate 7 to limit the downward movement of the hook while the spring 22 will resist the upward movement of the hook.

It will be understood that I desire to comprehend within my invention such modifications as may be clearly embraced within the scope of my claims and invention.

Having thus fully described my invention, what I claim as new and desire to secure by Letters Patent, is:

1. In a coupler head, the combination of a stationary jaw and a lower freely movable jaw, and a coupler hook associated with said jaws, said coupler hook having yielding means acting directly thereon for maintaining it in coupling position.

2. In a coupler head, the combination of a stationary jaw and a lower freely movable jaw, a coupler hook associated with said jaws, said coupler hook having yielding means acting directly thereon for maintaining it in coupling position and means on said coupler hook for engaging with the lower jaw to yieldingly resist its movement in approaching the upper jaw.

3. In a coupler head, the combination of a stationary jaw and a lower freely movable jaw, a coupler hook associated with said jaws, said coupler hook having yielding means acting directly thereon for maintaining it in coupling position, means on said coupler hook for engaging with the lower jaw to yieldingly resist its movement in approaching the upper jaw and means on the lower jaw for limiting its movement away from the upper jaw.

4. In a coupler, the combination of a stationary upper jaw, a lower spaced movable jaw pivoted thereon, said jaws having converging surfaces for guiding a bail into a slot between said jaws and a pivotally mounted hook on the stationary jaw normally located in the space between said jaws.

5. In a coupler, the combination of a stationary upper jaw, a lower spaced movable jaw pivoted thereon, said jaws having converging surfaces for guiding a bail into a slot between said jaws, a pivotally mounted hook on the stationary jaw normally located in the space between said jaws and means on said hook for limiting its movement toward the lower jaw.

6. In a coupler, the combination of a stationary upper jaw, a lower spaced movable jaw pivoted thereon, said jaws having converging surfaces for guiding a bail into a slot between said jaws, a pivotally mounted hook on the stationary jaw normally located in the space between said jaws, means on said hook for limiting its movement toward the lower jaw and yielding means associated with said hook for resisting its upward movement and that of the lower jaw either with the lower jaw or independently thereof.

7. In a coupler, the combination of a stationary upper jaw, a lower spaced movable jaw pivoted thereon, said jaws having converging surfaces for guiding a bail into a slot between said jaws, a pivotally mounted hook on the stationary jaw normally located in the space between said jaws, means on said hook for limiting its movement toward the lower jaw, yielding means associated with said hook for resisting its upward movement and that of the lower jaw either with the lower jaw or independently thereof and means to limit the downward movement of the lower jaw.

8. In combination, a coupler, a bifurcated upper coupler jaw, a hook pivoted within said bifurcated jaw normally extending below it and a movable lower jaw pivoted on said bifurcated upper jaw to form a bail-receiving space between said jaws normally closed by said hook.

9. In combination, a coupler, a bifurcated upper coupler jaw, a hook pivoted within said bifurcated jaw normally extending below it, a movable lower jaw pivoted on said bifurcated upper jaw to form a bail-receiving

space between said jaws normally closed by said hook and yielding means for maintaining said hook in said position.

10. In combination, a coupler, a bifurcated upper coupler jaw, a hook pivoted within said bifurcated jaw normally extending below it and a movable lower jaw pivoted on said bifurcated upper jaw to form a bail-receiving space between said jaws normally closed by said hook and yielding means for maintaining said hook in said position, said lower jaw having a bifurcated inner end for engaging either side of said stationary jaw.

11. In a coupler, a slotted upper jaw having a bail-guiding face directed inwardly and downwardly, a pivoted hook within said upper jaw depending therefrom having a bail-engaging face in alignment with the upper jaw face, a pivoted lower jaw mounted on the upper jaw but spaced therefrom having a bail-engaging face directed inwardly and upwardly for normal engagement with said hook.

12. In a coupler, a slotted upper jaw having a bail-guiding face directed inwardly and downwardly, a pivoted hook within said upper jaw depending therefrom having a bail-engaging face in alignment with the upper jaw face, a pivoted lower jaw mounted on the upper jaw but spaced therefrom having a bail-engaging face directed inwardly and upwardly for normal engagement with said hook and yielding means for maintaining said hook in its lower position.

13. In combination, an upper stationary, bifurcated jaw, a pivoted hook located therein and depending therefrom, a shaft in said upper jaw for pivotally mounting said hook, said hook having spaced arms for mounting on said shaft, yielding means on said shaft engaging said jaw and said hook, a depending lug from the upper jaw, a shaft carried therein and a lower jaw having spaced arms pivoted on said shaft.

14. In combination, an upper stationary, bifurcated jaw, a pivoted hook located therein and depending therefrom, a shaft in said upper jaw for pivotally mounting said hook, said hook having spaced arms for mounting on said shaft, yielding means on said shaft engaging said jaw and said hook, a depending lug from the upper jaw, a shaft carried therein, a lower jaw having spaced arms pivoted on said shaft, said hook-engaging normally the upper surface of said lower jaw whereby the upward movement of said lower jaw will be yieldingly resisted by the hook and its yielding means.

In testimony whereof, I affix my signature.
SHERWOOD M. CHASE.
